[57] CLAIM

The ornamental design for a combined sink and colander, as shown and described.

DESCRIPTION

FIG. 1 is a perspective view taken from the top, front and left side of combined sink and colander showing our new design;

FIG. 2 is a top plan view thereof;

FIG. 3 is a cross-sectional view taken on line 3—3 of FIG. 2;

FIG. 4 is a cross-sectional view taken on line 4—4 of FIG. 2;

FIG. 5 is an enlarged cross-sectional view taken on line 5—5 of FIG. 2; and,

FIG. 6 is another perspective view taken from the top, front and left side thereof showing the collander in the other basin.

The fragmentary broken line representation of a countertop in FIGS. 1 and 6, and the broken line representation of holes in FIGS. 1 and 6 are for the purpose of illustration only and form no part of the claimed design.
